6 Claims. (Cl. 57—79)

1

This invention relates to stop mechanism for spinning frames of the type described in my prior application for Patent Ser. No. 707,680 of November 4, 1946, now Patent No. 2,500,343, issued March 14, 1950, in which a stop motion automatically operates under the control of a suction device by causing each sliver to pass in front of a suction orifice before being wound on the bobbin, so that upon breakage of the sliver or production of a single, a change in suction conditions is produced to cause actuation of the stop motion mechanism for automatically stopping the frame.

It is known in spinning frames to control the reversal of the bobbin rail of the frame by an oscillatory reversing bracket. Each time this bracket effects its angular stroke a reversing of the movement of the bobbin rail is produced, and for a short period the rail is free of any restraint. If a breakage of the sliver occurred during this reversal period, actuating the stop motion, it is possible that the released bobbin rail would fall by operation of the force of gravity.

It is an object of the present invention to provide an automatic stop mechanism which is placed under the control of the above mentioned stop motion to prevent stopping of the frame during an extremely short period when the bobbin rail is released at both ends of its stroke, and this at any amplitude of its stroke.

Other objects and advantages of the present invention will be apparent from the following specification by reference to the accompanying drawings, in which

Fig. 1 is a fragmentary view in elevation of a roving frame having a stop mechanism according to the invention.

Fig. 2 represents the reversing bracket with the contact of the automatic stopping device according to Fig. 1 in an intermediate position of operation, in which the stop is operative.

Figs. 3 and 4 show a modified reversing bracket in two positions of operations.

Referring to Figs. 1 and 2 the slivers 1 are fed by the roller 2 and wound up on bobbins 3 after passing before suction orifices 4 of a suction conduit 5 connected to a suction fan 6.

The suction conduit is formed with an enlarged cylindrical portion 7 in which can reciprocate a piston 8 having holes 8'. This piston 8 is guided by a rod 9 which projects outwardly from the cylinder and on the end of which is hingedly mounted on a pin 10 a lever 11 pivoting on a fixed axis 12 and carrying a mercury switch 13. This switch is disposed in the circuit 14 of a coil of

an electromagnet 15 adapted to attract a rod 16 which is normally locked by a bolt 17 and hingedly connected at 18 to another lever 19. This lever 19 is pivoted on a fixed axis 20 and urged to turn in the direction of the arrow f^1 , for example by a counterweight 21 or by a spring or other suitable means.

The lever 19 bears against a shoulder 22 of a releasing bar 23 connected to the shift fork 24 which is adapted to cause a driving belt not shown to pass from a driving pulley 25 to a loose pulley 26 of the frame.

The stop motion mechanism is completed by a lever 27 pivoting on a fixed axis 28. This lever 15 is engaged by means of a slot 27' on a pin 29 of the bar 23. Its other end is hingedly connected at 30 to a pawl 31 having one end formed as hook 32 adapted to cooperate with a projection 33 on the piston rod 9, while the opposite end of the pawl 31 cooperates with an inclined surface 34 formed externally on the bottom of the cylinder 7.

The operation of the stop motion is as follows:

When a sliver 1 breaks, the material delivered by the roller 2 is immediately drawn into the suction conduit 5 by the suction of the fan 6 and it cannot mix up with the adjacent rovings. When a single is produced, it is also sucked into the conduit 5 after a very short time.

When the material of the broken slivers is introduced into the suction conduit 5 it is drawn towards the piston 8 and produces plugging of the holes 8' of the piston. The suction of the fan 6 then produces a difference in pressure on opposite sides of the piston 8 in the cylinder 7 which pressure difference causes the piston to move in the direction of the arrow f^2 .

The rod 9 then acts on the lever 11 to oscillate the lever about its axis 12 and close the electric circuit 14 by tilting the mercury switch 13 to horizontal position. Closing of the electric circuit 14 energizes the coil 15 which attracts the rod 16 and disengages it from the bolt 17 so as to release the lever 19. This lever, owing to the action of the counterweight 21 turns on its pivot 20 and moves the releasing bar and the shift fork 24 in the direction of the arrow f^1 so as to cause the driving belt to pass from the fixed pulley 25 to the loose pulley 26.

Owing to the movement of the releasing bar 23 the lever 27 is rocked about the pivot 28, the end of the lever 27 carrying the pawl 31 is moved towards the left in Fig. 1 and the rear end of the pawl abandons the inclined surface 34 and the pawl rocks about the axis 30, so that the front

end portion of the pawl arm comes to rest on the projection 33 on the rod 9, whereby the hook 32 reaches over the projection on the left side thereof.

Closing of the electric circuit 14 can produce in any conventional manner a signal, for example a mechanical or a luminous or sonorous signal to draw the attention of the operator to the fact that the frame has stopped and to particularly designate the machine on which the stop occurred among a group of similar machines.

When the operator has pieced-up the broken sliver 1 or eliminated the single, the frame is started up again. For this purpose the releasing bar 23 is moved in the direction opposite to the arrow f^1 . By the intermediary of the lever 27 pivoting on the fixed axis 28, this bar 23 moves the hook 32 engaged on the projection 33 of the piston rod 9. The piston is thus returned to its operating position and is ready to operate again. At the end of the returning movement the pawl 31 engages with its end the inclined surface 34, so that the pawl is forced to tilt thereby causing the hook to disengage the projection 33 of the rod 9. The piston 8 which is now entirely free again can move in the direction of the arrow f^2 , as soon as a new breakage of the sliver 1 occurs.

The mechanism so far described is claimed in my above mentioned prior application and does not form a part of the present invention.

The bobbin spindles 60 are carried by the vertically movable bobbin rail 61. The change of direction at the two ends of the stroke of the rail are obtained in well known manner by a reversing bracket which is constituted by a member 62 oscillatably mounted on an axis 63 and effecting an angular displacement x which is always of the same extent for any length of stroke of the rail 61. The bracket 62 is provided with two eyelets 64 through which can slide a rod 65. The end of this rod carries a pin 66 engaged in a guide slot 67 formed on the rail 61. From the beginning until the end of forming the bobbins 3, the pin 66 advances at each stroke of the rail 61 in the guide slot 67 in the direction of the arrow f^4 . The distance L becomes shorter with any successive stroke and the rail makes continuously reduced movements while the bracket 62 always effects the same angular movement, x .

According to the present invention the bracket 62 is provided with two adjustable abutments 68 and 69 adapted to alternatively bear against the switches 70 and 71, respectively, which are mounted like pendulums on the axes 72 and 73, respectively.

These switches are disposed in series in the electric circuit 14 together with the switch 13 of the automatic stop motion above described.

The operation of the automatic stopping device is as follows:

When the rail 61 is not at the end of its stroke (Fig. 2) the switches 70 and 71 are maintained by gravity in a position in which the electric circuit is established at these switches and accordingly can be closed when the switch 13 is actuated by the piston 8 upon breakage of a sliver 1.

However, when the rail 61 is at one end of its stroke (Fig. 1) so that one of the abutments 68 or 69 bears against a switch 70 or 71, the circuit 14 is interrupted at the engaged switch and the switch 13 of the automatic stop motion cannot produce the closure of the circuit, and the movement of the frame cannot be stopped until the abutment 68 and 69 has released the engaged switch 70 or 71.

In the drawings conventional mercury switches have been represented. It is evident that any other convenient type of switches may be used for this purpose.

Figs. 3 and 4 represent a modification of the automatic cut-out device, according to which the reversing bracket 63 carries a toothed sector 73 which meshes with a pinion 74 the gear ratio being such that the pinion makes one revolution for one oscillation of the bracket 63, each time the bobbin rail 61 moves up or down. The pinion 74 is rigidly connected to a lever 75 which at the end of each stroke causes the switch 76 to tilt about the fixed axis 77 in one or the other direction so as to open the circuit 14 at each end of the stroke.

The opening periods may be modified either by changing the number of teeth of the pinion 74 or by changing the diameter of the contacting roller 78 at the end of the lever 75.

The shapes of the switches forming pendulums and of the members which move them are preferably so chosen that the period during which an automatic cut-out of the frame drive is impossible is as short as possible and comprises the instant during which the reversal of the movement of the bobbin rail is effected.

I claim:

1. In a spinning frame having a stop motion, the combination of electromagnetic means operative to initiate actuation of said stop motion, a bobbin carrying rail adapted to reciprocate substantially in the direction of the axis of the bobbin spindles, a suction conduit provided with a series of suction orifices, means for feeding a sliver in front of each suction orifice to said bobbins, means movable within the suction conduit in response to change in suction conditions therein, said electromagnetic means becoming operative upon displacement of said movable means due to a change in suction conditions in said conduit when a sliver breaks or a single is produced and broken sliver is drawn into the suction conduit, and means preventing said electromagnetic means from becoming operative when said bobbin rail is substantially at either end of its course.

2. In a spinning frame having a stop motion, a suction conduit provided with a series of suction orifices, a bobbin rail adapted to reciprocate substantially in the direction of the axes of the bobbin spindles, means for feeding a sliver to each of said bobbins, said suction orifices being each disposed in proximity of the path of a sliver passing to a bobbin whereby when a sliver is broken, the broken sliver will be drawn into the suction conduit, a wall member permeable to air movably disposed in said suction conduit and adapted to create difference in pressure acting at opposite sides of said permeable wall member in the suction conduit when material of a broken sliver accumulates at one face of said wall member and changes its permeability, electromagnetic means operative upon a pressure difference being so created to operate said stop motion, and means preventing said electromagnetic means from becoming operative when said bobbin rail is substantially at either end of its course.

3. In a spinning frame having a stop motion, a suction conduit provided with a series of suction orifices, a bobbin rail adapted to reciprocate substantially in the direction of the axes of the bobbin spindles, means for feeding a sliver to each of said bobbins, said suction orifices being each disposed in proximity of the path of a sliver

passing to a bobbin whereby when a sliver is broken, the broken sliver will be drawn into the suction conduit, a wall member permeable to air movably disposed in said suction conduit and adapted to create a difference in pressure acting at opposite sides of said permeable wall member in the suction conduit when material of a broken sliver accumulates at one face of said wall member and changes its permeability, electromagnetic means operative upon a pressure difference being so created to operate said stop motion, a switch disposed in series in the circuit of said electromagnetic means, and an actuating member for said switch operated by said reciprocating bobbin rail to open the switch when the bobbin rail is substantially at the end of its course, to prevent operation of said electromagnetic means during reversal of the bobbin rail movement.

4. A spinning frame as defined in claim 3, 20 wherein said actuating member for the switch connected in the circuit of the electromagnetic stop motion operating means is constituted by

the reversing bracket controlling the reversal of the bobbin rail movement.

5. A spinning frame as defined in claim 3, wherein said switch actuating member is constituted by the reversing bracket controlling the reversal of the bobbin rail movement, said bracket having two adjustable abutments cooperating each with a switch mounted in series in the circuit of said electromagnetic stop motion operating means to open the circuit during reversal of the bobbin rail movement.

10 15 6. A spinning frame as defined in claim 3, wherein said switch actuating member is constituted by the reversing bracket controlling the reversal of the bobbin rail movement, said bracket having a toothed sector, a pin meshing with said sector, and a switch operating arm moving with said pinion to actuate said switch during reversal of the bobbin rail movement.
